[57] CLAIM

The ornamental design for movable shelf divider, substantially as shown.

DESCRIPTION

FIG. 1 is a perspective view of a movable shelf divider showing my new design;

FIG. 2 is a front elevation view thereof;

FIG. 3 is a side elevation view thereof;

FIG. 4 is a further side elevational view thereof opposed to that of FIG. 3;

FIG. 5 is a top plan view thereof;

FIG. 6 is a bottom plan view thereof; and

FIG. 7 is a rear view thereof.

Fig. 2.

Fig. 3.

Fig. 4.
